DESIGN FOR A COSMETIC CASE

Samuel Fritzie, New York, N. Y.

Application April 18, 1944, Serial No. 113,297

Term of patent 3½ years

(Cl. D87—3)

To all whom it may concern:

Be it known that I, Samuel Fritzie, a citizen of the United States of America, residing in city of New York, county of New York, and State of New York, have invented a new, original, and ornamental Design for a Cosmetic Case, of which the following is a specification, reference being had to the accompanying drawing, forming part thereof.

Fig. 1 is a front perspective view of a cosmetic case showing my new design.

Fig. 2 is a perspective view of a cosmetic case in open position.

The back of the cosmetic case is substantially plain.

I claim:

The ornamental design for a cosmetic case, substantially as shown and described.

SAMUEL FRITZIE.
